BILLFOLD

Richard Hirschfelder, Chicago, Ill.

Application March 16, 1950, Serial No. 149,959

1 Claim. (Cl. 150—38)

1
My invention relates to improvements in billfolds.

One of the objects of my invention is the provision of a billfold of simple construction having means for dividing the billfold into a plurality of compartments, some of which are hidden, for the safekeeping of currency bills or papers so that the same are obscured from view.

Another object of my invention is the provision of means, within a billfold, which may be selectively positioned so as to form hidden or exposed compartments within the billfold, as desired.

Other and further objects and advantages of my invention will become apparent from the following description when considered in connection with the accompanying drawings in which—

Fig. 1 is an elevational view of the outer side of a billfold constructed in accordance with the present invention, and showing the auxiliary flaps in extended position.

Fig. 2 is a sectional perspective view, the section being taken substantially on line 2—2 of Fig. 1.

Fig. 3 is a view similar to Fig. 2 but showing one of the auxiliary flaps in folded condition.

Fig. 4 is a similar view showing both of the auxiliary flaps in folded condition.

Fig. 5 is an elevational view of the inner side of a billfold illustrating one of the auxiliary flaps partially projected from its normal position.

Fig. 6 is a view similar to Fig. 1 but showing another auxiliary flap partially projected from its normal position.

Fig. 7 is a cross sectional view taken substantially on line 7—7 of Fig. 5, and

Fig. 8 is a sectional perspective view, the section being taken substantially on line 8—8 of Fig. 5.

Referring to the drawings, wherein is shown a preferred embodiment of my invention, the numeral 10 indicates generally a billfold of conventional construction, the said billfold comprising an outer wall 11 and an inner wall 12, the said inner wall being joined to the outer wall along the ends and lower longitudinal edge to form a bill or paper receiving compartment. In the embodiment illustrated, the inner wall 12 comprises a pair of spaced pockets 13 and 14 formed by panel sections 15 and 16 respectively, integral with the outer wall 11 and an intermediate panel 17 projecting into the adjacent mouths of the pockets to form an uninterrupted wall. Panels 15 and 16 are formed with exten-

sions 15a and 16a which embrace the upper portions of the panel 17. The panels 15 and 16 each may be provided with a transparent window, such as 18, through which a card may be viewed.

Positioned between the outer and inner walls 11 and 12 respectively and secured to the ends thereof is a panel 19 having an integral flap 21. The panel 19 is scored along a longitudinal line so as to facilitate folding of the flap which has substantially the same area as the panel. The ends and the lower longitudinal edges of the flap 21 are free so that the flap may be withdrawn. The flap is adapted to fold flat against the panel 19 and when so folded provides an auxiliary compartment which effectively obscures any papers or bills positioned between the flap and the panel.

It will be apparent that the flap 21 and the panel 19 together form an intermediate wall which serves to divide the main compartment into two separate compartments, each of which when the billfold is open exposes the contents thereof.

A second auxiliary flap 22 is connected to the outer wall 11 and has a width substantially about one-third of that of the outer wall. The lower longitudinal edge and ends of the flap 22 are free and the flap is adapted to be folded inwardly and is intended to serve two functions, as will be presently explained. For example, in the position shown in Fig. 4, certain papers or bills may be separated from the other articles in the compartment adjacent the outer wall 11 by allowing the flap 22 to embrace the upper longitudinal edges of the articles which are desired to be separated. Thus, the flap 22 retains certain of the articles in separated relation and obscures only the same partially. It will be apparent that by moving the panel 19 and flap 21 so that the flap 22 embraces the upper longitudinal edges of the same, as illustrated in Fig. 8, two hidden compartments, thus, are formed, one being disposed between the outer wall 11 and the flap 21 and the other being disposed between the flap 21 and the panel 19. With the parts arranged as illustrated in Fig. 8, it will be apparent that only one open compartment is available for the reception of papers or bills, and in such position, the flap 22 may also be utilized to separate papers or bills within the said compartment, the flap then retaining certain of the bills or papers against the panel 19.

I claim:

A billfold comprising inner and outer walls secured along their ends and along one of their

longitudinal edges to form a compartment, a panel disposed between said walls and secured along the ends thereof, said panel extending longitudinally and dividing said compartment into two pockets open along an upper longitudinal edge, a flap integrally connected to said panel along its upper longitudinal edge and foldable against said panel to form an intermediate pocket opening closely adjacent the lower longitudinal edge of said panel, and a second flap connected to the upper longitudinal edge of said outer wall, said second flap being free at its ends and lower longitudinal edge and adapted to selectively embrace only the upper longitudinal marginal edge of said dividing panel to obscure the same from view when the billfold is open, or the second flap may rest adjacent said outer wall and provide a visible compartment between the outer wall and dividing panel.
